DEFORMABLE SELF-SUPPORTING EXPLOSIVE COMPOSITION

Cyril James Breza, Thorofare, and Clyde Oliver Davis, Wenonah, N.J., assignors to E. I. du Pont de Nemours and Company, Wilmington, Del., a corporation of Delaware

No Drawing. Filed Aug. 17, 1960, Ser. No. 46,044
5 Claims. (Cl. 52—5)

The present invention relates to a self-supporting explosive composition. More particularly, the present invention relates to a deformable self-supporting explosive composition. More particularly, the present invention relates to a deformable self-supporting explosive composition comprising a cap-sensitive crystalline high explosive compound admixed with a binding agent and to a method of fabricating the composition.

This application is a continuation-in-part of our prior application Serial No. 666,221, filed June 17, 1957, now abandoned.

For many applications of explosives, the use of crystalline high explosive compounds, such as PETN or RDX, in the form of self-supporting units rather than as crystals or granules would be highly desirable. For example, for the method of joining metallic elements described in U.S. Patent 2,367,206, issued January 16, 1945, sleeves of explosives are provided by containing the charge of granular high explosive in a rigid annular container made of paper and the like. These containers must be slipped over the metallic element and a metal sleeve and, thus, are subjected to considerable stress which, in many cases, causes rupture of the necessarily rigid container. Moreover, because of their rigidity, many of these explosive units break during storage and transport. Obviously, elimination of this container and provision of a deformable self-supporting unit would be very advantageous. Moreover, the desirability of using flexible sheets of explosive which are cohesive enough to be cut, molded, or otherwise deformed to metal as in the method of work-hardening described in detail in U.S. Patent 2,703,297 issued March 1, 1955, is expressed in this patent. In shaped charge perforators, the substitution of cohesive, self-supporting contoured shapes of explosive for the presently used charges of explosive which are pressed into a casing would facilitate the preparation of such perforators. Such self-supporting explosive units, however, are not presently available.

Heretofore, many attempts have been made to prepare self-supporting high explosive compositions for use in the aforementioned applications. However, the results of these attempts have been far from satisfactory. For example, nitrocellulose has been proposed as a binding agent for crystalline high explosives in order to effect the formation of the explosive into self-supporting units such as the sleeves of explosive discussed previously. However, nitrocellulose was found to be unsuitable for this use because the resultant units lacked the required cohesiveness. Moreover, the hazardous nature of this material complicates its handling and, thus, its use in such applications. Wax also has been added to high explosives in efforts to prepare self-supporting explosive units. However, the quantity of wax required to provide the necessary cohesiveness in these units desensitizes the units with the result that they cannot be shot.

In further efforts to prepare self-supporting explosive compositions, rubber has been incorporated into crystalline high explosives. However, not only is a homogeneous mixture of pure rubber and the explosive difficult to prepare, even when a volatile dispersing agent is used, due to the tendency of the components of the mixture to segregate, but also the resultant mass is difficult to work.

2

For example, if the dispersing agent is removed from the mixture before formation of the desired shapes, the rubber explosive mixture is formed into the desired shapes, for example into sheets by rolling, only with great difficulty, if at all, due to the resiliency of this mixture. On the other hand, when the mixture containing the dispersing agent is worked up into the required shapes, for example by casting or extrusion, subsequent evaporation of this agent from the units results in undesirable void spaces in the units, which voids cause desensitization and nonuniform density. The problem of nonuniform density is further complicated by the fact that the consistency of the mixture before extrusion or casting cannot be maintained uniform. Moreover, the resiliency of rubber explosive sheets, when and if obtained, is such that the sheet will not retain the requisite deformation but will spring back to the original shape. Thereby, the use of such sheets is difficult, if not impossible, in many applications of sheet explosive.

Accordingly, an object of the present invention is to provide a self-supporting deformable explosive composition prepared in a simple and safe manner. Another object of the present invention is to provide a self-supporting explosive composition which can be formed readily into explosive units of the desired shape and having uniform density. A further object of the present invention is to provide a method by which high-density sheets of a self-supporting deformable explosive composition can be fabricated readily and safely. A further object of the present invention is to provide self-supporting explosive units which can be deformed and will remain in the desired deformed state.

We have found that the foregoing objects may be achieved when we provide an explosive composition comprising a cap-sensitive crystalline high explosive compound, such as pentaerythritol tetranitrate (commonly referred to in the explosives arts as "PETN") or cyclotrimethylenetrinitramine (commonly referred to in the explosives arts as "RDX"), and a binding agent consisting of an organic rubber and a thermoplastic terpene hydrocarbon resin.

In accordance with the present invention, 92.5 to 70 parts by weight of a cap-sensitive crystalline high explosive compound is admixed with 7.5 to 30 parts by weight of a binding agent comprising 25 to 75% of an organic rubber and 75 to 25% of a thermoplastic terpene hydrocarbon resin, the binding agent being in solution and thereafter the solvent is removed from the mixture by evaporation. The resulting dry solvent free composition is cohesive and formable and, thus, is easily and safely worked by pressing or rolling to form explosive sheets or other shapes having a high density and a high detonation velocity.

The following examples serve to illustrate specific embodiments of the explosive composition of the present invention. However, they will be understood to be illustrative only and not as limiting the invention in any manner. Unless designated otherwise, the parts in the examples are parts by weight. The thermoplastic terpene hydrocarbon resin used in all the examples was "Piccolyte" a commercially available material and composed essentially of polymers of β -pinene. Of course, as is evident, other thermoplastic terpene hydrocarbon resins could be substituted for the "Piccolyte."

EXAMPLE 1

Water-wet PETN in the amount of 283 parts (dry basis) was mixed with 125 parts of a hexane solution containing 50 parts of a 50/50 mixture, by weight, of butyl rubber and the terpene resin ("Piccolyte" S-10 and S-70 grades) over a period of 10 minutes with vigorous agitation. Then, the water present on the surface of the

mass was decanted, and the mass, which was glue-like and sticky, was removed from the mixer and spread out on a tray to air-dry overnight. After the water and hexane were evaporated, the PETN-binding agent mixture (85/15, weight ratio), which was no longer sticky, was rolled into sheets between brass rollers.

The sheets had a density of 1.45 grams per cc. and had an impact sensitiveness, as determined by the standard drop test (5-kg. weight), of 12 inches (50% detonation point). The sheets could be initiated by No. 6 blasting caps, and the velocity of detonation was 7200 meters per second. In appearance, the sheets were strong, flexible, and their resilience was so slight that when bent they retained their deformed shape. After one month's storage (normal and low temperature), no change occurred in the sheets. Immersion of the sheets in water (10 p.s.i.) had no effect upon them.

EXAMPLE 2

Two mixes were prepared in accordance with the method of Example 1, with the exception that the proportions of elastomer and terpene resin in the binding agent were varied. The properties of the sheets formed from these mixes are listed in the following table.

Table I

Mix	Ratio of Elastomer/Resin in Binder	Density (g./cc.)	Impact Sensitiveness (Drop Test in Inches)	Velocity of Detonation (m./sec.)
A 1	75/25	1.43	11	6,800
B 2	25/75	1.45	17	7,200

¹ Tough sheet with good flexibility, slightly stiff and slightly resilient

² Tough sheet with good flexibility, limp and slightly sticky, no resilience

Sheets made from both mixes could be initiated by No. 6 caps.

EXAMPLE 3

A number of mixes were prepared by the aforescribed method from PETN and a 50/50 mixture of butyl rubber and the terpene resin. In these mixes, the proportions of PETN to binder were varied as shown in the following table which summarizes the properties of the sheets prepared from these mixes.

Table II

Mix	PETN/Binder (parts)	Density (g./cc.)	Impact Sensitiveness (Drop Test in Inches)	Velocity of Detonation (m./sec.)
I	77.5/22.5	1.45	21	6,600
II	80/20	1.41	19	7,000
III	82.5/17.5	1.60	15	6,900
IV	87.5/12.5	1.41	21	6,800
V	90/10	1.49	13	6,900
VI	92.5/7.5	1.35	18	6,900

All the sheets were strong and flexible with little resiliency and could be initiated by No. 6 caps.

EXAMPLE 4

Sheets were rolled from a mix prepared as described in Example 1 with the exception that polyisobutylene (commercially available as "Vistanex") was substituted for the butyl rubber. The mixture was rolled out into sheets which were strong and flexible and had a density of 1.41 grams per cc. In the standard drop test (5 kg. weight), the 50% detonations point of the sheet was 11 inches. The detonation velocity of the sheet was 6700 meters per second, and the sheet could be initiated by No. 6 caps.

EXAMPLE 5

An 85/15 mixture of RDX and binding agent (50/50 mixture of butyl rubber and the terpene resin) was prepared by the method of Example 1. The mixture was

rolled into sheets weighing 4 grams per square inch and having a density of 1.48 grams per cc. These sheets were strong and flexible and detonated at a velocity of 7100 meters per second. In the drop test (5 kg. weight) made on these sheets, the 50% detonations point was 26 inches. The sheets were initiated by No. 6 caps.

EXAMPLE 6

A flexible sheet explosive composition was prepared as in Example 1 consisting of 70% by weight PETN (dry basis) and 30% of the 50/50 butyl rubber-terpene resin binder. In this example, the PETN used was of a particle size within the range of 0.1-10 microns with an average maximum particle dimension of 0.1-2.0 microns.

The sheet had a density of 1.21 grams/cc. and had an impact sensitiveness, as determined by the standard drop test (5 kg. weight), of 56 inches (50% detonation point). The sheet could be initiated by a No. 6 blasting cap, and the velocity of detonation was 6500 meters/sec. The sheet was strong, flexible, retained any shape into which it was deformed, and exhibited good storage characteristics.

As may be seen by reference to the foregoing examples, the addition of an elastomer and a thermoplastic terpene hydrocarbon resin to a cap-sensitive crystalline high explosive compound results in a mass which is cohesive, flexible, and of only slight resilience. Due to these properties, the mass can be worked up into the desired form, for example, sheets, in a simple manner and without difficulty. The resultant forms have the cohesiveness, flexibility, and nonresilience required for their use in many applications of explosives, e.g. the previously mentioned joining method, and in addition, are water resistant, unaffected by storage under normal conditions or at low temperatures, and of high density.

Although the rolling of the mass into sheets has been exemplified and is claimed, the mass also can be worked up into other forms, for example the contoured shapes required for shaped charge perforators, by other processes such as molding. Moreover, the nature of the explosive mass is such that it can be formed into sheets by methods other than rolling, i.e. by slicing or cutting of the mass.

The high explosive component constitutes 92.5 to 70% of the explosive composition. The use of greater amounts of this component results in forms lacking the desired cohesiveness and having a tendency to crack, whereas the use of lesser amounts of the high explosive results in forms which will not detonate. Compositions within the present invention having lower proportions of the explosive will usually contain the explosive in a finely divided form to insure detonability. When the proper proportions of high explosive and binder are used, the sheets or other forms can be initiated by commercially available blasting caps and will detonate at velocities in the order of 7000 meters per second. The use of PETN, an organic nitrate, and RDX, a nitramine, which are representative cap-sensitive crystalline high explosive compounds, as this component of the explosive composition has been exemplified. However, the use of other cap-sensitive crystalline high explosive compounds is equally feasible. For example, other organic nitrates, such as "nitromannite," and other nitramines such as HMX (cyclotetramethylenetrinitramine) and ethylenedinitramine, also can be used. Moreover, a mixture of such compounds or of a high explosive compound such as PETN and a less sensitive material such as ammonium nitrate is suitable.

The binding agent constitutes 7.5 to 30% of the explosive composition and comprises a mixture of 25-75% of an organic rubber and 75-25% of a thermoplastic terpene hydrocarbon resin. As shown in Example 2, increasing the proportion of the rubber increases the resilience of the explosive composition, and when the rubber constitutes more than 75% of the binding agent the composition is unsatisfactorily resilient. On the other hand, the use of less than 25% of the rubber in the binder gives

a composition which is very difficult to form and lacks strength and cohesiveness.

Butyl rubber and polyisobutylene were used to prepare the mixes described in the examples because they are representative and readily obtainable rubber products. However, any organic rubber may be used in preparing the explosive composition of the present invention. Such materials include natural rubber and synthetic rubbers such as GR-S rubber, neoprene, polysulfide rubber (commercially available as "Thiokol"), Buna N, chlorosulfonated polyethylene (commercially available as "Hypalon" S-2), etc.

Thermoplastic terpene resins are readily available commercially in either solid form or in solution. These resins are prepared in a well-known manner by the polymerization of β -pinene containing minor amounts of α -pinene and dipentene in the presence of a Friedel-Crafts catalyst, such as anhydrous aluminum chloride, according to the techniques described in detail by Kirk-Othmer, "Encyclopedia of Chemical Technology," Interscience Publishers, Inc. (1954), vol. 13, pages 702-3. The resins have the empirical formula $(C_{10}H_{16})_n$ wherein "n" represents the degree of polymerization. The latter may be varied over a wide range to yield polymers of low or relatively high average molecular weights. Resins having average molecular weights as high as 1200 to 1250 are known; such resins having a softening point in the range of 125°-135° C. The softening point is, of course, a function of average molecular weight and thus characterizes a particular resin in this regard. The various grades of the well-known "Piccolyte" resins are designated in this manner and the softening points of "Piccolyte" S-10 and "Piccolyte" S-70 thus are 10° C. and 70° C., respectively. These particular "Piccolyte" resins are very convenient to work with and yield an explosive composition of the type described having excellent workability and other physical properties in line with the objectives of the invention. The use of these particular resins is by no means critical to the invention, however, and the novel compositions of the present invention may be prepared with any grade of "Piccolyte" or other hydrocarbon terpene resin.

Although a variety of methods can be used to prepare sheets of the explosive composition, the method described in Example 1, i.e. admixing the high explosive with a solution of the rubber and resin, drying the mixture to drive off the solvent, and thereafter rolling the dried mass, is simple and gives very good results, especially with respect to the uniformly high density obtained in the sheets, and thereby is preferred. Any one of a wide variety of hydrocarbon solvents can be used in mixing the composition, and the mixture can be dried in a number of ways, for example air drying at ambient temperatures or hot air drying on trays or by supplying heat directly to the mixer to evaporate the solvent.

An attendant advantage of the explosive composition of the present invention resides in the fact that water is incompatible with the mixture of rubber and resin and thus separates out of the mixture and can be removed by decantation or suction, residual quantities of water being removed by evaporation during the drying of the mixture. Thus, the high explosive can be added in the water-wet state, in which state it is inherently safer than in the dry form. Of course, when hygroscopic components are used in the composition, the presence of water is to be avoided.

An additional feature of the explosive composition of the present invention is the fact that by application of a thin layer of a pressure-sensitive adhesive to the surface of the formed unit, e.g. the sheet, the unit will adhere to surface of another object. This feature makes the use of the composition especially advantageous in an application such as the afore-discussed metal hardening method. For example, sheets could be formed from the composition, a

layer of the adhesive could be placed on one surface of the sheets, and then a layer of crepe release paper could be placed upon the adhesive. When one of these sheets was to be used in metal hardening, the release paper would be removed and the adhesive surface of the sheet would be pressed against the surface of the metal to be hardened to give a strong bond between the sheet and the metal.

Although the invention has been described in detail in the foregoing, it will be apparent to those skilled in the art that many variations are possible without departure from the scope of the invention. We intend, therefore, to be limited only by the following claims.

We claim:

1. An explosive composition consisting essentially of a cap-sensitive crystalline high explosive compound selected from the class consisting of the organic nitrates and nitramines admixed with a binding agent consisting of 25-75% by weight of an organic rubber and 75-25% by weight of a thermoplastic terpene hydrocarbon resin, said high explosive compound constituting 92.5-70% by weight of said explosive composition, said composition having the ability to deform in shape when subjected to mechanical pressure or manipulation and to hold itself in any shape into which it is thus formed when the pressure is released whereby the composition may be molded or shaped at room temperature into a self-supporting physical form of any desired size and configuration.
2. An explosive composition according to claim 1, wherein the high explosive compound is a member of the group consisting of pentaerythritol tetranitrate and cyclotrimethylenetrinitramine.
3. An explosive composition according to claim 1, wherein the organic rubber is a member of the group consisting of butyl rubber and polyisobutylene.
4. An explosive composition in sheet form comprising a cap-sensitive crystalline high explosive compound selected from the class consisting of the organic nitrates and nitramines admixed with a binding agent consisting of 25-75% by weight of an organic rubber and 75-25% by weight of a thermoplastic terpene hydrocarbon resin, said high explosive compound constituting 92.5-70% by weight of said explosive composition, said composition having the ability to deform in shape when subjected to mechanical pressure or manipulation and to hold itself in any shape into which it is thus formed when the pressure is released whereby the composition may be molded or shaped at room temperature into a self-supporting physical form of any desired size and configuration.
5. A method of fabricating a self-supporting deformable explosive composition in sheet form which consists of intimately admixing 92.5-70% by weight of a cap-sensitive crystalline high explosive compound selected from the class consisting of the organic nitrates and nitramines with 7.5-30% by weight of a binding agent consisting of 25-75% by weight of an organic rubber and 75-25% by weight of a thermoplastic terpene hydrocarbon resin, said binding agent being in solution, removing the solvent from the mixture by evaporation, and thereafter rolling the solvent free mixture into sheets.
